DISINTEGRATION OF MATRIX, MUD BALLS,
ETC.

John Treadwell Bullwinkel, Brooklyn, N. Y.

Application August 16, 1935, Serial No. 36,472

2 Claims. (Cl. 209—6)

This invention relates to the treatment and disintegration of softer materials, such as agglomerated clay, so-called clay balls or mud balls, etc., admixed with harder materials. More particularly the invention relates to the treatment or disintegration of phosphate matrix, containing pebble phosphate embedded in or intermixed with sand and clay, so that the pebble phosphate can be readily separated and recovered. The invention includes both an improved method of treatment or disintegration and improved apparatus therefor.

The invention, in its broader aspects, is applicable to the disintegration of various materials, containing harder and softer ingredients which it is desired to separate from each other, and where so-called logs and scrubbers are now commonly used for bringing about such disintegration of the softer materials, and the washing of the softer materials away from the undisintegrated harder materials.

The improved process and apparatus of the invention are, however, of particular value in connection with the disintegration of phosphate matrix and similar materials, and will be more particularly described in connection therewith.

Phosphate matrix consists principally of phosphate in the form of pebbles ranging from minute sizes to pebbles larger than one inch in size, but for the most part of pebbles less than one-half inch in size. These phosphate pebbles are embedded in clay and sand both of which have to be removed by washing and screening to recover the pebble phosphate. Before the washing and screening can be done the matrix must be disintegrated.

Disintegration of phosphate matrix does not mean disintegration in the sense of grinding or crushing, but means, in the case of phosphate matrix, a loosening or separating by water of the phosphate pebbles from the clay and sand so that the disintegrated material can be screened and washed and the pebble phosphate recovered therefrom.

The disintegration of phosphate matrix is an important and necessary step preliminary to the washing and screening treatment because it otherwise is quite impracticable and impossible to recover a marketable product by washing and screening.

Phosphate matrix varies considerably. A matrix containing a high percentage of sand disintegrates more easily than a matrix containing a high percentage of clay. In some conditions matrix is found which is very "stiff" and difficult

to disintegrate. Such stiff matrix, difficult to disintegrate, causes the greatest trouble in washing and screening, because the lumps or balls of matrix, frequently called "mud balls", will remain in the washing process to the end and thus contaminate and lower the quality of the finished phosphate product. To avoid this contamination of the product, the larger lumps of matrix containing phosphate, and also pebbles of phosphate of the same size or larger, are usually thrown away as debris. The smaller lumps or mud balls are usually subjected to some sort of a scrubbing treatment, such as with logs or scrubbers, etc., to effect the necessary disintegrating action. It is important to disintegrate all mud balls thoroughly and as quickly as possible because under some conditions they will pick up rock and other mud balls and then become more troublesome.

One method of disintegration of phosphate matrix which has been practiced for many years is the hydraulic process in which the disintegration is accomplished during the mining of the matrix with hydraulic guns, using pressures of around 200 pounds. It is common practice, in hydraulic mining of matrix, to reject at the beginning of the washing process, the larger mud balls by the use of separators which are usually the first units of the washing process. This rejection of the larger mud balls, etc., to debris, causes a loss of the phosphate which the mud balls contain.

Another method of disintegrating the phosphate matrix is that described in my prior Patent No. 1,901,221, granted March 14, 1933, in which the phosphate matrix is mined by dry mining and disintegrated by the use of soaking pits. In such process, after the matrix has been disintegrated by soaking and souping in the soaking pit, the larger lumps or mud balls are rejected from the washing process, by the use of separators, and returned again to the soaking pit. This requires a rehandling of this part of the matrix, with consequent additional cost. These larger mud balls are usually of the stiffest and most difficult kind of matrix to disintegrate; and they may require, therefore, rehandling a number of times before they have been disintegrated sufficiently for the washer to handle.

With the oversize mud balls which are lost in the hydraulic process, by rejection into the waste or debris, and with the oversize mud balls which are rehandled and recirculated in the dry mining process above referred to, there are some lumps of bed rock which, if permitted to enter into the phosphate product, will contaminate the product and lower its grade. Accordingly, even with

satisfactory disintegration of the oversize mud balls, the phosphate product would be contaminated by such bed rock unless some means of eliminating the bed rock separately from the washing process is provided.

In the usual washing and screening operations, the logs and scrubbers used do not satisfactorily handle and disintegrate large mud balls or lumps of matrix, when the feed of mud balls or large lumps is a high percentage compared with the rock; and the logs and washers do not eliminate or reject the bed rock. I have found in some cases that when feeding mud balls to logs under certain conditions, the logs not only do not disintegrate the mud balls, but the clay gums up and chokes the logs. I have also found that scrubbers, under some conditions, instead of disintegrating the mud balls, merely reduce them somewhat in size. I have also found that both logs and scrubbers tend to grind away the softer pebbles of phosphate while grinding away the clay balls, with resultant loss not only of tonnage of phosphate product recovered, but also a more serious loss in grade and quality, since the softer phosphate pebbles, which are more easily ground away by mechanical handling, are usually the highest grade of phosphate.

The pebble phosphate rock, recovered from the phosphate matrix, as a result of the disintegrating, washing and screening treatments, etc., is usually sold as 68% grade, 70% grade, 72% grade, 75% grade, and 77% grade, and there are premiums in the selling price for each higher grade, and the highest qualities demand the highest premium. It will be noted from these grades that the matter of one percent or two percent in quality is important and valuable, and therefore any loss in quality occasioned by unnecessary handling and treatment, or harsh treatment in the washing and screening of the pebble phosphate, is detrimental.

I have found that mud balls, which are difficult to treat by present methods, can be rapidly and effectively disintegrated by supplying them, together with water, to a disintegrator, hereinafter described, in which the mud balls or lumps of matrix, while immersed in water, are subjected to the action of a submerged horizontal screen, which serves to support the material during its disintegration, and with rapid relative movement of the material and screen during the disintegration.

The disintegrator which I have found particularly effective is one with a rapidly rotatable horizontal screen carried by a vertical shaft and arranged within and/or near the bottom of a stationary cylinder which is submerged in a tank or sump, and with the water level in the tank above the level of the screen and above the level of the material fed to the disintegrator, so that the material will be kept under water during its disintegration. Provision is made for feeding the material to be disintegrated and also for feeding water to the cylinder above the screen; and provision is also made for withdrawing the disintegrated material from the tank or sump below the screen.

The rapidly rotatable perforated screen has openings of suitable size for the particular material to be disintegrated. The holes may be circular holes of as much as one and one-quarter inches or one and one-half inches in diameter; or the holes may be of other size and shape such that the disintegrated material will pass therethrough. The screen is arranged so that it can

be rapidly rotated, the rate of rotation varying somewhat with the diameter of the screen, and the quantity of material to be disintegrated.

I have found that the material can be disintegrated with the use of a stationary screen, instead of a rapidly rotatable screen, provided rapid relative movement of the material on the stationary screen is caused by rapidly rotating arms carried by suitable vertical shafts; but I have found the use of a rapidly rotatable screen mounted within and near the bottom of a stationary vertical cylinder, a particularly effective arrangement of apparatus for accomplishing the desired disintegration of mud balls and phosphate matrix material.

The invention will be further described in connection with the accompanying drawings, but it will be understood that the invention is illustrated thereby but is not limited thereto.

In the accompanying drawings:

Fig. 1 shows one form of the disintegrator, in vertical section and with parts in elevation;

Fig. 2 is a top view of the apparatus of Fig. 1;

Fig. 3 is a flow sheet illustrating the treatment of phosphate matrix when hydraulic mining is used, with the disintegrating treatment of the present invention included in the flow sheet, and with the operations which are eliminated from the old process shown in dotted lines;

Fig. 4 is a flow sheet of the process in which dry mining of the phosphate matrix is employed, followed by the soaking of the material, as described in my prior Patent No. 1,901,221, with the disintegrating treatment of the present invention included in the flow sheet; and with the portion of the flow sheet, when the present invention is not employed, shown in dotted lines; and

Fig. 5 is a flow sheet showing the application of the present invention to the disintegration of phosphate matrix mined by dry mining and without further preliminary disintegration before it is subjected to the present disintegrating process.

One form of disintegrator is illustrated in Figs. 1 and 2. As illustrated, two tanks or sumps 1 and 2 are arranged adjacent to each other, these tanks or sumps being of suitable size and construction. Within the tank 1 is a stationary cylindrical member 3 suitably supported; and within this cylinder and near the bottom is a rotatable screen 4 supported and rotatable by the shaft 5 driven by the pulley 6. The screen is made of suitable material, such as perforated metal, of a strength adequate to support the material undergoing disintegration. The cylinder is shown as imperforate, but it may be perforated near its lower end, where submerged, to permit discharge of disintegrated material through the holes in the cylinder as well as through the holes in the screen. The mud balls or matrix to be disintegrated are supplied to the space inside the cylinder 3 through the feed pipes or feed chutes 7. Water is supplied to the space inside the cylinder 3 through the water supply pipe 8. A discharge pipe 9 leads from the space in the tank 1 below the perforated screen through the centrifugal pump 10 by means of which the disintegrated material is withdrawn and pumped through the pipe 11 to the usual washing and screening machinery. The pump 10 is shown as driven by the electric motor 12.

Near the bottom of the cylinder 3 is an opening with a gate or closure 13 adapted to be raised by the operating rod 14 and handle 15. When the gate 13 is opened, the space inside the cylinder is connected with the pipe 16 for discharging the bed rock to the debris sump or tank 2.

In the operation of the apparatus, the water level is kept sufficiently high so that the rotating screen and the material supported thereby are submerged, and so that the disintegration takes place while the material is so submerged.

The rotating screen can be rotated at varying and different rates of speed or rotation. The rate may be around 100 to 150 revolutions per minute for a screen around 3 or 4 feet in diameter; but the rate of rotation can be varied according to the quantity of material to be disintegrated.

In carrying out the process, with the apparatus illustrated, the so-called mud balls or clay balls or other lumps of the matrix material to be disintegrated are fed through the pipe or chute into the top of the space formed by the cylindrical casing 3 and the perforated screen 4. The material is supported by the rotating screen and effective agitation is brought about by the relative movement of the screen and material supported thereby, inasmuch as the stationary cylindrical casing 3 tends to retard rotation of the water enclosed therein while rapidly rotating screen tends to cause the material supported thereon to rotate therewith. The result is an effective relative movement of the screen and of the material supported thereby, and an effective disintegration of the material.

When the material has been disintegrated to sizes smaller than the openings in the perforated screen, the disintegrated material falls through the screen into the space in the tank below the screen, and from there it is then pumped through the pipe 9 and by means of the centrifugal pump 10 to a higher elevation where it is fed to the usual washing and screening units. Water is added to the disintegrator continuously for the purpose of providing water for suspension of the clay separated from the mud balls by the disintegrating treatment, and for use in pumping away the material after it has been disintegrated. In the continuous operation of the process, there will be a continuous or intermittent feed of the mud balls or other material to be disintegrated and a continuous supply of water, together with a continuous withdrawal of the disintegrated material from the space below the screen. As a result, there is a downward movement of the water in the cylinder 3, and downwardly through the perforated screen, so that relatively fresh water is in contact with the material above the screen, and the clay and sand, as they are separated from the mud ball, are carried in suspension in the water downwardly through the screen, and are pumped by the centrifugal pump to the subsequent steps of the process.

The mud balls may be admixed with bed rock. This bed rock, if permitted to remain in the phosphate product, will cause a lowering of the quality of the product. The bed rock which is much harder than the mud balls does not disintegrate in the disintegrator except to a very limited extent, and therefore remains on the top of the perforated rotating screen. Soft bed rock may be disintegrated and pass off with the slimes. When sufficient bed rock has accumulated in the disintegrator, which is easily determined by the noise as it tumbles around, it can be easily discharged from the disintegrator by opening the gate 13 which permits the revolving screen to throw the bed rock out of the disintegrator by centrifugal force. The bed rock thus rejected is collected in the sump 2 which is shown as having the same level of water therein as in the tank 1 so that

there will not be any objectionable loss of disintegrated material when the bed rock is discharged.

When the bed rock is not present to an objectionable extent in the disintegrator, I have found that it has a helpful effect upon the disintegration of the mud balls. As the disintegrator can easily reject the bed rock, when it has accumulated to an objectionable extent, and as the bed rock is helpful in the disintegration of the mud balls, the bed rock serves a useful function in promoting the disintegration, although its presence and action are not necessary to obtain the desired disintegration.

The perforated rotatable screen may have strips or baffles attached to its top to cause greater agitation of the material to be disintegrated; but satisfactory disintegration can be obtained with a perforated metal plate or screen without such added elements.

The size of the holes in the screen will vary somewhat with the nature of the material being treated. The holes should be large enough to permit the pebbles of phosphate to pass therethrough. I have found a screen with one and one-quarter inch circular holes suitable for the treatment of mud balls; and screens with holes of one and one-half inch diameter have also been used; as well as screens with holes rectangular in shape, one-quarter inch by one-half inch in size.

I have found that the larger lumps of matrix, mud balls and bed rock which are commonly discarded to waste in the hydraulic process of disintegration, can be treated in the apparatus and in accordance with the process of the present invention with consequent increase in recovery of phosphate and with elimination of bed rock of size larger than the openings used in the screen.

The flow sheet illustrated in Fig. 3 illustrates the process, with the parts omitted in the old process shown in dotted lines. As illustrated in this flow sheet, the phosphate matrix in the mine is disintegrated with a hydraulic gun and the disintegrated material is pumped to a washer and then goes to a separator where the oversize and undersize materials are separated from each other. The undersize material goes in the usual washing and screening operation. The oversize material, of a size of more than about one and one-half inches, in the old process, is considered waste or debris and is discarded, although it contains phosphate rock.

According to the present invention this oversize material, made up of mud balls, bed rock, etc., and containing recoverable phosphate, is subjected to the disintegrating treatment above described and the separated phosphate, etc., is then passed to the usual washing and screening operations while the waste or bed rock, being free from recoverable phosphate, forms the waste or debris.

I have also found that in the dry mining process in which the matrix is disintegrated in water in soaking pits, as described in my prior Patent No. 1,901,221, the large mud balls which are ordinarily separated out in the separators with four inch openings, and returned to the soaking pit for resoaking and rehandling, can be quickly, easily and more economically disintegrated by the disintegrator and disintegrating process of the present invention, thereby saving rehandling costs and rejecting bed rock, and with a betterment of quality of the phosphate rock recovered.

The flow sheet of Fig. 4 illustrates the applica-

tion of the present process and apparatus in connection with the dry mining of phosphate rock and the treatment of the material in the soaking pit; and, in this figure, the process is shown in 5 dotted lines as it is carried out when the present process is not employed.

As illustrated in the flow sheet, when the present process is not employed, the oversize lumps or mud balls, of more than four inches in size are 10 separated out and returned to the soaking pits, and refractory mud balls may require successive return and rehandling in this way.

When the present process is employed, this 15 separation and return of mud balls for further soaking is eliminated, and the disintegrated material from the soaking pit is passed to a washer and then to a submerged screen separator of about three-eights inch size. The undersize goes to the usual washing and screening operations; 20 while the oversize goes to the disintegrating treatment of the present invention and then to a separator where the remaining oversize, mostly coarse rock, goes to the debris pile, while the recovered phosphate goes to the usual washing and 25 screening operations.

I have also found that phosphate matrix which 30 has been mined by the dry mining process, and which has not been disintegrated otherwise, can be satisfactorily and economically disintegrated 35 by feeding the dry matrix, together with water to the disintegrator of the present invention, and by subjecting it to the disintegrating process of the present invention. Such dry mined matrix can be transported from the mines, and subjected 40 to the present disintegrating process, without any preliminary treatment such as treatment in the soaking pit of my said prior Patent No. 1,901,221. When the matrix is thus directly treated, I have found that the side of the screen openings can be 45 conveniently reduced to a size slightly larger than that of the largest pebbles to be required. Products of different sizes can be made with additional disintegrators, and by additional disintegrating treatments, according to the present invention, using appropriate sizes of openings of the screens.

The flow sheet of Fig. 5 shows the small number 50 of steps and operations involved in the preliminary handling and disintegration of the phosphate matrix. The matrix is mined by dry mining as by the use of a dragline or shovel, and is transferred by cars or otherwise, while in a dry undisintegrated state, and fed to the disintegrator; and subjected to the disintegrating treatment 55 of the present invention. As a result, the matrix is thereby disintegrated to an extent such that it can pass advantageously through the usual washing and screening operations; and these operations can be carried out in an advantageous manner with the material which is disintegrated 60 in this way.

The present process and apparatus are also applicable to the treatment of phosphate matrix, mud balls, etc., at various stages in the handling of the material, wherever mud balls are present, 65 or wherever an effective and rapid disintegration of the matrix is desired. The use of the process enables practically the maximum recovery of phosphate to be obtained, at low cost, and with high quality of products.

70 The disintegrating operation of the present invention should be distinguished from grinding operations of grinding machines, since the action is accomplished by the rolling around of the material on the rotating screen, while submerged 75 in water. As the material is retained on top of

the screen until it has been sufficiently disintegrated to pass through the screen, the disintegrator controls the necessary time element required for disintegration of clay, etc. in water. Some matrix and some clays require longer time than others for disintegration, and the rotating screen holds back the material until it has had the necessary time required for its effective disintegration.

75 The process and apparatus of the present invention present many advantages in the treatment and handling of phosphate matrix, mud balls, etc., among them the following: A greater recovery of phosphate pebbles can be obtained from the phosphate matrix disintegrated by hydraulic mining by treatment of the mud balls which are normally rejected as debris or waste in such mining operations; a recovery of higher quality of pebble phosphate is obtainable by reducing the quantity of phosphate matrix in the 20 form of mud balls that ordinarily would require treatment in logs or scrubbers; mud balls can be disintegrated in a more convenient and less costly way by eliminating the necessity of rehandling and recirculating mud balls one or more times; the bed rock contained in or admixed with the mud balls can be separated and rejected while recovering the phosphate from the mud balls and balls of matrix with which the lumps of bed rock 25 are associated; the disintegration by the present process is accomplished at reduced cost because the horse power required to operate the disintegrator of the present invention is very much less than the horse power required to operate either logs or scrubbers of equal capacity; the disintegrating action is less harsh than that of scrubbers and enables the recovery of greater quantities 30 of phosphate to be obtained, because of the avoidance or minimizing of harsh treatment of the soft pebble phosphate.

35 The apparatus and process of the present invention can be used to advantage to eliminate either or both the logs and scrubbers to facilitate the removal of clay and the rejection of determined oversize product; or the rejection or recovery of a determined undersize product; or the rejection or recovery of both a determined undersize and a determined oversize product.

45 The present invention makes possible the simplification of the treatment of phosphate debris which is mined by dry mining operations. Where a soaking pit treatment is used to disintegrate the matrix, the use of the present process enables the initial separators to be eliminated, as well as the cost of operating such separators. The present process moreover makes possible the elimination of the soaking pit treatment, by supplying the disintegrated dry matrix directly to the disintegrating process and apparatus of the present 50 invention.

55 The process and apparatus of the present invention have the further advantage that, while the operation is a continuous one, the time element can nevertheless be controlled as required by different materials, such as phosphate matrix and clay, for disintegration in water to a determined size. The more easily disintegrated materials will be more readily disintegrated and removed while the more refractory and more difficultly disintegratable material will be given the 60 necessary time of contact to insure effective disintegration; and this can all be accomplished as a part of a continuous process.

65 The invention has been more particularly described in connection with the treatment of 75

phosphate matrix and the separation of phosphate rock from admixed clay, etc.; and the invention is of particular value for the treatment of such materials.

Other material than phosphate matrix or admixed phosphate rock clay, etc. can similarly be treated, and with similar advantage, where it presents a similar problem for its handling, and where apparatus such as logs and scrubbers are now used. In general, the present invention makes possible the disintegration of softer materials, such as clay, mud balls, clay balls, etc., in aggregated form, from harder materials, by subjecting the aggregated clay or softer material to combined mechanical action and the action of water under conditions which promote the dissipation of the aggregated soft material into a finely divided state such that it can be washed away from the harder and undisintegrated material.

I claim:

1. The method of disintegrating phosphate aggregates consisting of pebble phosphate having a covering of a softer material which comprises maintaining a relatively stationary mass of the aggregates at a substantial depth in a chamber having a surrounding stationary wall and enclosed within an outer chamber, rotating against the bottom of said relatively stationary mass of aggregates a substantially flat horizontal screen having openings of a size to retain at least some of the aggregates but to pass at least some of the pebble phosphate after removal of the softer covering material, rotating said screen

at a rate sufficiently rapid to remove softer material from the retained aggregates by attrition until they are of a size to pass through the screen, substantially continuously supplying aggregates and water above the screen, maintaining said mass of aggregates substantially submerged in water, and withdrawing from beneath the screen water and material which passes through the screen.

2. The method of disintegrating phosphate aggregates consisting of pebble phosphate having a covering of a softer material which comprises maintaining a relatively stationary mass of the aggregates at a substantial depth in a chamber having a surrounding stationary wall and enclosed within an outer chamber, rotating against the bottom of said relatively stationary mass of aggregates a substantially flat horizontal screen having openings of a size to retain at least some of the aggregates but to pass at least some of the pebble phosphate after removal of the softer covering material, rotating said screen at a rate sufficiently rapid to remove softer material from the retained aggregates by attrition until they are of a size to pass through the screen, substantially continuously supplying aggregates and water above the screen, maintaining said mass of aggregates substantially submerged in water, withdrawing from beneath the screen water and material which passes through the screen, and withdrawing from the inner chamber above the screen material which is too large to pass through the screen.

JOHN TREADWELL BULLWINKEL.
